UNITED STATES PATENT OFFICE

154,443

DESIGN FOR AN EXTENSION FOR AUTOMOBILE ENGINE EXHAUST PIPES

Charles A. Trowbridge, Roxborough, Pa., assignor to Ontario Research Corporation, Philadelphia, Pa., a corporation of Pennsylvania

Application September 13, 1948, Serial No. 148,571

Term of patent 14 years

(Cl. D14—6)

To all whom it may concern:

Be it known that I, Charles A. Trowbridge, a citizen of the United States, residing in Roxborough, Philadelphia County, Pennsylvania, have invented a new, original, and ornamental Design for Extension for Automobile Engine Exhaust Pipes, of which the following is a specification, reference being made to the accompanying drawing, forming a part thereof, in which:

Fig. 1 is a perspective view from the outer end thereof of an extension for automobile engine exhaust pipes, showing my new design;

Fig. 2 is a perspective view from the inner end thereof;

Fig. 3 is a side elevational view thereof;

Fig. 4 is a top plan view thereof;

Fig. 5 is an outer end elevational view thereof; and

Fig. 6 is an inner end elevational view thereof.

I claim:

The ornamental design for an extension for automobile engine exhaust pipes, substantially as shown.

CHARLES A. TROWBRIDGE.
